ADOLPH PHILIPPI, OF ELIZABETHPORT, NEW JERSEY.

Letters Patent No. 78,126, dated May 19, 1868.

IMPROVED RAILWAY-SWITCH PLATE.

The Schedule referred to in these Letters Patent and making part of the same.

TO ALL WHOM IT MAY CONCERN:

Be it known that I, ADOLPH PHILIPPI, of Elizabethport, in the county of Union, and State of New Jersey, have invented a new and improved Railroad-Switch Plate; and I do hereby declare that the following is a full, clear, and exact description thereof, which will enable others skilled in the art to make and use the same, reference being had to the accompanying drawings, forming part of this specification.

Figure 1 represents a plan or top view, partly in section, of my improved switch-plate.

Figure 2 is a vertical transverse section of the same, taken on the plane of the line $x\ x$; fig. 1.

Figure 3 is a vertical longitudinal section of the same, taken on the plane of the line $y\ y$, fig. 1.

Similar letters of reference indicate corresponding parts.

This invention relates to a new switch-plate, which is so made that the rails have an elastic bearing, and that they can be removed and replaced at will without removing the switch-plate.

The invention consists of a cast-iron bed, with upward-projecting flanges around all sides, which serve to prevent a wrought-iron plate, and an interposed wooden layer, from sliding off the bed; and in arranging a series of blocks upon the wrought-iron plate, which blocks are shaped similar to a letter T , and serve to hold the rails down.

A, in the drawing, represents the cast-iron bed-plate. The same is of suitable length, width, and thickness, and from its edges project upward flanges, $a\ a$, at the sides, and flanges $b\ b$ and $c\ c$ at the ends, as shown. Upon the bed A is placed, within the flanges $a\ b\ c$, a wooden or other elastic plate, B, upon which a wrought-iron plate, C, rests. By means of bolts or rivets, $d\ d$, the plates A, B, and C are securely fastened together, and by means of bolts, e , to the sleeper, if there is one used.

Upon the surface of the plate C are secured the rail-holding blocks D and E. The outer blocks, D, are L-shaped, and are, by means of bolts or rivets, f , fastened to the bed and the plates B, C, as shown. The inner blocks, E, are T-shaped, and are, by means of bolts or rivets, g , held in place, as is clearly shown in fig. 2.

The blocks D rest partly upon the flanges a , as shown, and also abut against the same, and against a shoulder, h , formed on them, as in fig. 1, and have thus a firm bearing. Still they can, by taking off the bolts or rivets f , be easily removed, so as to allow the removal and replacement of the outer set of rails; and when they are out, the next blocks, E, can also be removed to allow the removal and replacement of the inner rails. From the flanges a project inward blocks or lugs, i , which serve to arrest the switch-bars, to prevent them from moving too far to one side.

I claim as new, and desire to secure by Letters Patent—

A switch-plate, consisting of the bed-plate A, elastic bed B, and plate C, and of the removable blocks D and E, all made and operating substantially as herein shown and described.

A. PHILIPPI.
